Fig. 6

To all whom it may concern:

Be it known that I, David S. Morishita, a citizen of the United States, residing at Honolulu, in the Territory of Hawaii, have invented a new, original, and ornamental Design for an Orange Peeler, of which the following is a specification, reference being had to the accompanying drawing, forming part thereof.

Figure 1 is a perspective view of an orange peeler showing my new design;

Figure 2 is a top plan view;

Figure 3 is a bottom plan view;

Figure 4 is a cross-sectional view taken on the plane of line 4—4 of Figure 1;

Figure 5 is a cross-sectional view taken on the plane of line 5—5 of Figure 1; and

Figure 6 is a cross-sectional view taken on the plane of line 6—6 of Figure 1.

I claim:

The ornamental design for an orange peeler, as shown.
